FOREIGN PATENT DOCUMENTS

GB	2391292	2/2004

Primary Examiner—Holly N. Baynam*Assistant Examiner*—Cynthia M. Chin(74) *Attorney, Agent, or Firm*—Keisling Pieper & Scott PLC; David B. Pieper; Trent C. Keisling**CLAIM**

The ornamental design for a fuel cell marker, as shown and described.

DESCRIPTION

FIG. 1 is a left side view of the fuel cell marker;
 FIG. 2 is an enlarged back view of the design of FIG. 1;
 FIG. 3 is a right side view of the design of FIG. 1;
 FIG. 4 is an enlarged front view of the design of FIG. 1;
 FIG. 5 is a top view of the design of FIG. 1; and,
 FIG. 6 is a bottom view of the design of FIG. 1.
